(57) **CLAIM**

The ornamental design for an article of furniture, as shown and described.

DESCRIPTION

FIG. 1 is a front perspective view of an article of furniture embodying the new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines shown in the drawings are for the purpose of illustrating environmental subject matter and form no part of the claimed design. Stipple shading is added to convey surface contouring; the stipple shading is not to be understood as conveying a particular surface finish.
